Primary Examiner — Paula Allen Greene*(74) Attorney, Agent, or Firm* — Plumsea Law Group, LLC(57) **CLAIM**

The ornamental design for a headphone, as shown and described.

DESCRIPTION

FIG. 1 is a perspective view of a headphone showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines to the logo outline on the exterior headphone in FIGS. 1-5 and 7 represent the bounds of the claimed design. The broken lines immediately adjacent the shaded areas represent the bounds of the claimed design. All other broken lines are directed to environment; the broken lines form no part of the claimed design.
